Primary Examiner — Rebekah A Caruso

Assistant Examiner — Cole Sanders Holman

(57) CLAIM

The ornamental design for a record player, substantially as shown and described.

DESCRIPTION

FIG. 1 is a front perspective view of record player, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view in an open state thereof;

FIG. 9 is an enlarged detail view of area 9 in FIG. 1;

FIG. 10 is an enlarged detail view of area 10 in FIG. 1;

FIG. 11 is an enlarged detail view of area 11 in FIG. 2;

FIG. 12 is an enlarged detail view of area 12 in FIG. 2; and,

FIG. 13 is an enlarged detail view of area 13 in FIG. 5.

The broken lines in the drawings illustrate portions of the record player, which form no part of the claimed design. The dot dash broken lines depict the boundaries of the enlarged views and form no part of the claimed design.

1 Claim, 13 Drawing Sheets
